UNITED STATES PATENT OFFICE

150,072

DESIGN FOR A WRIST SUN DIAL

John H. Klaine, Fort Thomas, Ky.

Application July 31, 1947, Serial No. 140,641

Term of patent 3½ years

(Cl. D42—8)

To all whom it may concern:

Be it known that I, John H. Klaine, a citizen of the United States, residing at Fort Thomas, in the county of Campbell and State of Kentucky, have invented certain new, original, and ornamental Design for a Wrist Sun Dial, of which the following is a full, clear, and exact description, reference being had to the accompanying drawings, forming a part thereof.

In the drawings:

Figure 1 is a front elevation of a wrist sun dial showing my new design.

Figure 2 is a side elevation of the wrist sun dial shown in Figure 1 with the strap shown fragmentarily.

Figure 3 is an enlarged fragmentary sectional view taken on line 3—3 of Figure 1.

The essential features of my design are shown in full lines.

I claim:

The ornamental design for a wrist sun dial, as shown and described.

JOHN H. KLAINE.
